UNITED STATES PATENT OFFICE.

JOSEF FREISLINGER, OF VIENNA, AUSTRIA.

INTERNAL-COMBUSTION ENGINE PROVIDED WITH AN AUXILIARY CHARGING PUMP.

Application filed February 9, 1926, Serial No. 86,978, and in Austria February 16, 1925.

This invention relates to an internal combustion engine provided with an auxiliary charging pump, in which before the beginning of the compression stroke a supplementary charge (air or mixture) is forced into the air or mixture of fuel and air, already contained in the working cylinder, by means of the auxiliary charging pump.

The engine according to the present invention possesses also the economical advantages of a construction in which the working chamber is rendered adjustable by the provision of an auxiliary piston.

The essential feature of the present invention consists in that each working piston and the auxiliary piston are surrounded or enclosed by a sleeve valve, which valves control the working cylinder, the pump and the inlet for admitting the auxiliary charge.

One mode of carrying out the present invention is illustrated by way of example on the accompanying sheet of drawings in which—

Fig. 1 shows a four stroke engine in longitudinal section.

Fig. 2 is a longitudinal section through the casing with the control of the auxiliary piston in elevation and the cover of the casing removed.

Figs. 3 and 4 are sectional views of the casing, the sections being taken on lines III—III and IV—IV respectively of Figs. 1 and 2.

The cylinder casing 1, 2 is closed by covers 3, 4 and 5, and sleeves or liners 6 and 7, to which auxiliary pistons 8 and 9 respectively are secured, are movably arranged in the casing. Screw-threaded-holes 10 and 11 respectively, provided in the heads of pistons 8—9, serve for the attachment of sparking plugs. The sleeves 6 and 7 with the auxiliary pistons 8 and 9 are operated by oscillating levers 14 and 15 respectively, whose pins rest in bearings 16 and 17. Sliding members 18 and 19 are arranged on the oscillating levers 14 and 15 and their pins are led in guides 20 and 21 respectively. The guides, consisting of slides, are mounted reciprocably in the cover 3 or in the casing and, as shown by the lines A—B and C—D

in Fig. 2, are inclined at an angle to one another in the indicated directions. The oscillating levers 14 and 15 are operated by eccentric rods 22 and 23 respectively. The eccentrics or cranks 25 and 26 are arranged on a cam-shaft 24 and are driven by the engine-shaft with half the number of revolutions of the latter by means of toothed wheels 27 and 28. The auxiliary pistons 8, 9 and the working pistons 12, 13 are surrounded by a pair of sleeve valves. The inner sleeve valves 29 and 30 are operated by connecting rods 31 and 32 respectively and the outer tubular slides 33 and 34 are driven by connecting rods 35 and 36, the said rods being operated by the shaft 24, whereby the outer sleeve valves 33, 34 are in advance of the inner sleeve valves 29, 30. Each pair of sleeve valves controls the corresponding cylinder and is provided with admission and exhaust ports at the end of the sleeve disposed adjacent to the combustion chamber as well as at the end of the sleeve disposed adjacent to the crank-casing. In the illustrated embodiment the time of opening and closing the ports of the pairs of valves 29, 33 and 30, 34 respectively, disposed adjacent to the combustion chamber, are displaced to each other for two strokes. During the first stroke, the working cylinder sucks in air or a mixture of fuel and air through the admission channels 37 and 38 as well as through the admission ports of the pairs of sleeves 29, 33 and 30, 34 arranged at the side of the combustion chamber during the inward stroke of the working piston 12 and 13 respectively. As soon as the working pistons 12 and 13 have passed the inner dead centre position, the pair of sleeves 29, 33 and 30, 34 respectively close the admission channels 37 and 38 respectively and uncover the slot of a by-pass channel 43, disposed at the crank-side, which establishes communication between the crank-casing and the working cylinder, so that at the beginning of the compression an auxiliary charge is added to the cylinder-charge. As soon as this auxiliary charge is admitted, the acting sleeve valve of the working cylinder closes the slot of the by-pass channel and now

commences the second stroke, the compression by the working pistons 12 and 13, whereby air or a mixture of fuel and air is simultaneously sucked into the crank-casing. Thereby the auxiliary piston 8 and 9 respectively limits the corresponding compression or combustion space. As soon as the desired compression has been accomplished, ignition takes place at 10 and 11 by means of the spark plugs. Now follows the third stroke, the expansion of the gases of combustion, whereby during the inward motion the working pistons 12 and 13 compress the charge in the crank casing already sucked in behind the same, in order that the same can be supplied as next auxiliary charge into the corresponding working cylinder in the described manner. The charge of the crank casing is effected during the outward motion of the working pistons 12 and 13 by way of the openings 39, 40, which are controlled also by the sleeve valves. The exhaust takes place by way of the opening 41, 42, which are controlled by the sleeve valves. If the working pistons 12, 13 move to the inner dead centre position during the suction stroke, thus toward the crank casing, the auxiliary pistons 8, 9 closing up the corresponding combustion chamber are moved outward and increase the effect of suction by increasing the contents of the cylinder. After compression and ignition the auxiliary pistons 8, 9 move inward, thus toward the crank casing, and reach their innermost position at the end of the exhaust stroke. Thereby the head of the auxiliary piston comes very close to the head of the working piston, so that the gases of combustion are completely pushed out of the cylinder. The stroke of the auxiliary pistons is adjustable in order to regulate the compression-chamber. The stroke is adjusted by raising or lowering the guide-slides 20 and 21, in which the sliding members 18 and 19 of the oscillating levers 14 and 15 respectively are rotatably mounted by means of pins. As shown in Fig. 2, the slides 20 and 21 are inclined to each other, whereby during the adjustment of the stroke the inner dead centre position of the auxiliary piston is maintained and only the outer dead centre position is varied according to requirement. The present invention is just as well applicable to two stroke engines or to engines working with any other kind of strokes.

I claim—

1. In an internal combustion engine, a combustion cylinder provided with intake and exhaust ports and an auxiliary intake port, a working piston operating in said cylinder, an auxiliary piston in said cylinder, a pair of sleeve valves surrounding said pistons and controlling said ports, and means for varying the throw of the auxil-

iary piston with relation to the throw of the working piston.

2. In an internal combustion engine, a combustion cylinder provided with intake and exhaust ports and an auxiliary intake port, a working piston operating in said cylinder, an auxiliary piston in said cylinder, a pair of sleeve valves surrounding said pistons and controlling said ports, an actuating shaft driven from the crank shaft of the engine, means operated by the actuating shaft for reciprocating the auxiliary piston and sleeve valves, and means for varying the throw of the auxiliary piston with relation to the throw of the working piston. 80

3. In an internal combustion engine, a combustion cylinder provided with intake and exhaust ports and an auxiliary intake port, a working piston operating in said cylinder, an auxiliary piston in said cylinder, a pair of sleeve valves surrounding said pistons and controlling said ports, and means for operating the auxiliary piston and the sleeve valves in timed relation to each other and to the working piston. 90

4. In an internal combustion engine, a combustion cylinder provided with intake and exhaust ports and an auxiliary intake port, a working piston operating in said cylinder, an auxiliary piston in said cylinder, a pair of sleeve valves surrounding said pistons and controlling said ports, means for operating the auxiliary piston and the sleeve valves in timed relation to each other and to the working piston, and means for varying the throw of the auxiliary piston with relation to the throw of the working piston. 100

5. In an internal combustion engine, a combustion cylinder provided with intake and exhaust ports and an auxiliary intake port, a working piston operating in said cylinder, an auxiliary piston in said cylinder, a pair of sleeve valves surrounding said pistons and controlling said ports, a shaft driven from the engine shaft, means actuated by said shaft for operating said sleeve valves, an oscillating arm connected with the auxiliary piston, and an eccentric on said shaft operatively coupled to said arm. 110

6. In an internal combustion engine, a combustion cylinder provided with intake and exhaust ports and an auxiliary intake port, a working piston operating in said cylinder, an auxiliary piston in said cylinder, a pair of sleeve valves surrounding said pistons and controlling said ports, a shaft driven from the engine shaft, connecting means between said shaft and said sleeve valves for operating the latter, a sleeve connected with the auxiliary piston, an oscillating arm connected with said sleeve, and an eccentric on said shaft and coupled to said arm. 115

7. In an internal combustion engine, a combustion cylinder provided with intake and exhaust ports and an auxiliary intake

port, a working piston operating in said cylinder, an auxiliary piston in said cylinder, a pair of sleeve valves surrounding said pistons and controlling said ports, means for operating said valves and said auxiliary piston in timed relation to each other and to the working piston, and adjusting means asso-

ciated with the operating means for the auxiliary piston for varying the action of said operating means and accordingly varying 10 the throw of the auxiliary piston with relation to the throw of the working piston.

In testimony whereof I affix my signature.

JOSEF FREISLINGER.
